UNITED STATES PATENT OFFICE

93,212

DESIGN FOR A SUNBONNET

Samuel J. Goldsmith, Chicago, Ill.

Application June 18, 1934, Serial No. 52,217

Term of patent 3½ years

To all whom it may concern:

Be it known that I, SAMUEL J. GOLDSMITH, a citizen of the United States, residing at Chicago, in the county of Cook and State of Illinois, have invented a new, original, and ornamental Design for Sunbonnets, of which the following is a specification, reference being had to the accompanying drawing, forming a part thereof:

Figure 1 of the drawing is a plan or top view of a sunbonnet embodying the new design;

Figure 2 is a side view of the sunbonnet; and Figure 3 is a bottom view.

I claim:

The ornamental design for a sunbonnet substantially as shown.

Signed at Chicago, Illinois, this 15th day of June, 1934.

SAMUEL J. GOLDSMITH.
